UNITED STATES PATENT OFFICE.

HERMAN J. WECKWERTH, OF GERMANIA, WISCONSIN.

DESIGN FOR A MANDOLIN-BODY.

SPECIFICATION forming part of Design No. 31,077, dated June 27, 1899.

Application filed May 18, 1899. Serial No. 717,383. Term of patent 14 years.

To all whom it may concern:

Be it known that I, HERMAN J. WECKWERTH, a citizen of the United States, residing at Germania, in the county of Marquette 5 and State of Wisconsin, have invented and produced a new and original Design for a Mandolin-Body; and I do declare the following to be a full, clear, and exact description of the same, reference being had to the accompanying drawings, forming a part thereof.

Figure 1 is a perspective view showing all parts of my design. Fig. 2 is a cross-section on the line 2 2 of Fig. 1.

As shown in the drawings, the leading or 15 material feature of my design may be said to consist in the specific shape of the body of the mandolin, although details in its shape and design are also important. Said body B in plan view is substantially coffin-shaped, 20 with the head of the coffin adjacent the tail-piece T, the outer corners C rounded, and the

foot of the coffin adjacent the neck N. Two crescent-shaped openings O are provided in the face at about the relative positions shown.

The sectional view illustrates the precise 25 configuration of the two parts or members which make up said mandolin-body. Said members curve outwardly away from each other slightly, and they have at their edges meeting portions P, which are overhung 30 slightly by flanges F at the top and bottom.

Having described my invention, what I claim as new, and desire to secure by Letters Patent, is—

The design for the body of a mandolin, as 35 herein shown and described.

In testimony whereof I affix my signature in presence of two witnesses.

HERMAN J. WECKWERTH.
